UNITED STATES PATENT OFFICE.

GEORGE ILSLEY ROBERTS, OF NEW ROCHELLE, NEW YORK.

TRAP OR SEPARATOR.

SPECIFICATION forming part of Letters Patent No. 703,610, dated July 1, 1902.
Application filed February 7, 1902, Serial No. 93,038. (No model.)

To all whom it may concern:

Be it known that I, GEORGE ILSLEY ROBERTS, a citizen of the United States, residing in New Rochelle, Westchester county, and State of New York, have invented certain new and useful Improvements in Steam or Water Traps or Separators, of which the following is a specification, reference being had to the accompanying drawings.

My invention relates to the improvement of that style of steam or water trap or separator shown and described in Letters Patent of the United States granted to me under date of August 3, 1897, and May 31, 1898, Nos. 587,560 and 604,844, and has for its present object the saving of heat from the water of engine condensation itself, as well as the saving of the heat abstracted from the steam or vapor by or during the separation, withdrawal, and removal of any contained grease, oil, lubricant, or other foreign matters and the making use of the same or any additional heat derived from or discarded by said steam or vapor as a means for heating or assisting in the heating of water for boiler-feed or other uses and purposes.

My improvements consist in the special construction, arrangement, and combination of the several parts, portions, or details comprising the apparatus, as hereinafter shown, described, and claimed.

Referring to the accompanying drawings, Figure 1 represents a central longitudinal section of an apparatus embodying my improvements. Fig. 2 represents a transverse section of the same looking toward the coil carrying partition. Fig. 3 represents an outer or end view of the same, showing a detail of the attachments at the water end of the apparatus.

Similar letters of reference designate like parts or portions in all the figures.

Letter A designates a main shell inclosing the several compartments of the apparatus. The shell may of course be constructed of any desired shape, form, or configuration. It is here shown cylindrical in outline.

Letter B designates an upper portion or compartment set off for the reception of the exhaust-steam from engine or power plant from which grease, oil, lubricant, or other material are to be separated and extracted.

Letter C designates a lower portion or compartment set off for the reception of the extracted grease, oil, lubricant, or other material extracted from the steam or vapor.

Letter D designates bars, clips, or other open means for carrying the baffling devices E for separating and extracting purposes.

Letter F designates a transverse partition extending, as shown, from beneath the steam or vapor outlet at B² downwardly to the bottom of main shell A.

Letter H designates an end portion or compartment set off for the reception of all return waters from the heating plant.

Letters B' and B² designate admission and discharge openings for the steam or vapor passing through compartment B, the cleansed steam passing regularly out at B² for use in steam heating or like low-pressure purposes.

Letters C' and H' designate the usual gage attachments for indicating drip and water levels in compartments C and H.

Letter I designates a pump-governing device operated by the float I' to supply or cut off the steam to said pump. The suction of the pump is connected to outlet-pipe K² as a means for emptying compartment H. This pump-governing device may, however, be dispensed with and any other well-known means made use of for emptying said compartment.

Letters C² and H² designate outlets for blowing out compartments C and H after usual methods.

Letter G designates a plurality of branch heating-compartments, bent tubes, or coils projecting from the walls or partition F of compartment H into compartment C, the inner portions of said compartments, tubes, or coils connecting with and allowing the contents of compartment H to enter and circulate through. Such chambers or coils are preferably located above and below the surface level of the grease, oil, lubricant, or other material in compartment C, so that their contents shall be exposed to and receive all the heat possible from the surrounding steam or vapor or the contained drip material.

Letter K designates one or more pipe connections through which all the water returns, drips, drainings, and discharges coming from the steam-power, steam using or

heating systems reach compartment H for storage or reheating.

K' designates an inlet branch pipe and controlling-valve.

5 K² designates an outlet branch pipe and controlling-valve.

K³ designates a special connection between the return-pipe K and outlet-pipe K².

10 K⁴ designates a pipe branch from return-pipe K, leading directly to pump for boiler-feed or other purposes.

Letter L designates a pipe and valve connection between compartments B and H, whereby additional heat may be transmitted

15 to the contained water of compartment H. Such transmission may be made more direct by passage through partition F, controlled by a valve to open or close such passage.

L' designates a special live-steam connection in case extra heat may be required. It is branched into pipe connection L.

Letter P designates a special pipe branch for the admission of any required additional feed or the extra water to compartment H.

20 25 It is enlarged at one portion to admit a steam-supply either from compartment B or the live-steam branch L'. This steam-supply is distributed by means of a special discharge or outlet L³ within said enlarged portion of 30 water admission P and is made perforate or otherwise as a means for disintegrating the steam or heating medium, so that it shall the more readily mingle with the liquid to be heated.

35 The several pipe connections entering or communicating with compartment H may be extended or adapted to discharge either into the upper or lower portions of the same.

In the operation of the device as illustrated the steam to be clarified or relieved of its suspended grease, oil, lubricant, or other matter is entered at the receiving-nozzle B', passes through compartment B and its contained baffles E for cleansing purposes,

40 and passes out through nozzle B² for further use, the said impurities, grease, oil, lubricant, or other matter being dropped or deposited within the lower compartment C.

The grease, oil, lubricant, or other deposits 45 naturally contain and carry with them a good quota of heat. One of the objects of the invention being to save this heat, the branch heating-compartments, bent tubes, or coils G are projected into said compartment C as

50 branches or extensions of compartments H, and their water contents are exposed to and receive heat from the surrounding greasy drip material or from the steam or vapor above.

55 50 The water-compartment H is a receptacle for all the clean-water returns of the steam-using plant, an object of the invention being to keep this contained water at a high temperature for boiler-feed or other purposes and

5 to, if necessary, reinforce the quantity of water passing through compartment H. Communication is arranged for between compart-

ments B and H for the admission of heat and through pipe P for the admission of extra water. Clean steam passes from compartment B at its outlet end to compartment H and carries heat to the contained water. When additional water is required beyond that furnished by the usual returns, steam is admitted to the water-piping P at its enlarged portion, where it mingles with the admitted water to raise it to any required temperature for boiler-feed or like purposes.

What I claim, and desire to secure by Letters Patent, is—

1. The combination, in a steam-trap, of a grease-extracting compartment provided with steam inlet and outlet openings, a drip-receiving compartment, and a return-water compartment provided with a plurality of 85 branch bent tubes extending from the walls of said return-water compartment into said drip-receiving compartment, substantially as and for the purposes set forth.

2. The combination, in a steam-trap, of a 90 grease-extracting compartment provided with steam inlet and outlet openings; a drip-receiving compartment; a return-water compartment, and controlled means for admitting steam from said grease-extracting compartment into said return-water compartment, substantially as and for the purposes set forth.

3. The combination, in a steam-trap, of a 100 grease-extracting compartment, provided with steam inlet and outlet openings; a drip-receiving compartment; a return-water compartment provided with branch water-heating compartments extending into said drip-receiving compartment; means for admitting steam from the grease-extracting compartment, and controlled means for admitting reinforce live steam and reinforce-water, substantially as and for the purposes set forth.

4. The combination, in a steam-trap, of a 110 grease-extracting compartment, provided with steam inlet and outlet openings; a drip-receiving compartment; a return-water compartment; a reinforce-admission pipe connecting with said return-water compartment, 115 a perforated steam-jet inclosed within said reinforce-admission pipe, for heating the reinforce water as it passes through substantially as set forth.

5. The combination, in a steam-trap, of a 120 grease-extracting compartment, provided with steam inlet and outlet openings; a drip-receiving compartment; a return-water compartment, means for admitting reinforce-water to the said return-water compartment, 125 and a steam-jet connection between the grease-extracting compartment and an enlarged portion of the reinforce-water connection, substantially as and for the purposes set forth.

GEORGE ILSLEY ROBERTS.
